UNITED STATES PATENT OFFICE.

HERBERT E. PUTNEY, EDGAR H. ECKERT, AND MILTON D. PUTNEY, OF TOLEDO, OHIO.

MAGAZINE-FUSE.

SPECIFICATION forming part of Letters Patent No. 761,908, dated June 7, 1904.

Application filed December 5, 1902. Serial No. 133,991. (No model.)

To all whom it may concern:

Be it known that we, HERBERT E. PUTNEY, EDGAR H. ECKERT, and MILTON D. PUTNEY, citizens of the United States, residing at Toledo, in the county of Lucas and State of Ohio, have invented a new and useful Improvement in Magazine-Fuses, of which the following is a specification.

Our invention relates to a magazine-fuse for electric circuits, and has for its object to provide a device of the kind having a plurality of safety-fuses each insulated from the others and adapted to be readily connected in circuit with a lead-conductor in succession as needed to replace a burned-out fuse and that may also be used as a switch to make or break the circuit.

The objects of our invention are accomplished as hereinafter described, and illustrated in the drawings, in which—

Figure 1 is an isometric view of a magazine-fuse constructed in accordance with our invention. Fig. 2 is a transverse section through the same in a vertical plane. Fig. 3 is a side elevation of a bearing. Fig. 4 is a side elevation of a magazine-fuse arranged to operate as a switch. Fig. 5 is an illustration showing electrical means to rotate the magazine. Fig. 6 is a plan view of a dial used in connection with the mechanism illustrated in Fig. 4 to indicate the fuse that is in circuit. Fig. 7 shows a plurality of fuses mounted upon a non-conducting board, which is arranged to travel in ways between two binding-posts of a lead set on opposite sides of the ways and successively connect the fuses with the posts.

A preferred embodiment of our invention is shown in Fig. 1 of the drawings, in which 1 designates a fuse-board of non-conducting and incombustible material, to which standards 2, having bearings 3, are suitably secured, and in the bearings there is journaled an arbor 4, having an end portion 5 projecting a suitable distance from an adjacent bearing 3. Between the bearings the arbor is preferably formed angular to receive and rotate a sleeve 6, which is mounted on the arbor, the sleeve being also of non-conducting and incombustible material.

The sleeve is provided at each end with spiders 7, preferably integral with the sleeve; but they 50 may be separate and suitably mounted on the arbor at each end of the sleeve.

Spiders 7 are provided with an equal number of radial arms 8, and the arms of the spiders are so arranged that each arm of one spider 55 radiates in the same radial plane with an arm of the other spider. Centrally in the angles between the radial arms of the spiders are formed integral therewith the webs 9 of less radius and thickness than the arms, thereby 60 forming side recesses 10 concentrically around the hubs of the spiders between the radial arms, with the free ends of the arms projecting beyond the webs 9.

Upon each web 9 there is mounted a fuse-terminal 11, the body portion of which is bifurcated to bestride the web, with the bifurcations extending radially toward the hub in the recesses 10, and each terminal is secured in such position by a bolt through the bifurcations and the web.

Each fuse-terminal 11 is provided with a winding-post 12, having a cross-head 13 formed as a cleat and preferably provided with a central notch 14. The post may be 75 formed integral with the body portion of the terminal, but is preferably a detachable stud-screw threaded into a suitable orifice in the body of the terminal, the head of the screw being T-shaped to form a suitable winding-cleat for the fuse.

To opposite winding-posts 12 from spider to spider are secured the fuse-wires 15 by placing their end portions in the notches 14 and then winding them around the cleats 13 85 in a figure 8 loop and twisting them back on the body of the wire. By thus securing the fuse-wires to the winding-posts when the fuse is burned out only that portion of the fuse between the twisted end portions is destroyed, 90 whereby any welding of the wire to the posts, such as frequently occurs where binding-posts are used and which practically unfits the posts for further use, is entirely avoided and the loose ends of the fuse are prevented from swinging 95 into contact with other fuse-wires or their

terminals and forming short circuits therewith. The arms 8 between the fuse-terminals prevent arcing between the terminals. Each fuse-terminal is also provided with an integral radial blade 16, located opposite to the supporting-stud for the fuse. The blades are of a length to project beyond the radial arms 8 a suitable distance and are arranged to rotate edgewise. Upon the fuse-board near each spider are mounted binding-posts 17, to each of which an end of the severed lead 18 is secured, and each binding-post is provided with a pair of parallel contact-plates 19, which extend from the posts in position to receive between them the radial blades 16 and contact therewith successively as the sleeve is rotated, and thereby as a pair of blades, one at each opposite end of the sleeve, are brought into contact with the plates of the binding-posts the fuse connecting such pair of blades is brought into circuit with the lead. When a fuse is burned out, by partially rotating the arbor by the means hereinafter described the burned-out fuse is switched out and the next succeeding fuse is switched into circuit with the lead, as occasion requires, until the magazine is exhausted. As one means to rotate the reel thus formed to successively connect the several fuses in circuit with the lead we have provided a ratchet-wheel 20, which is rigidly mounted upon the end 4 of the arbor 5. Ratchet-wheel 20 is provided with ratchet-teeth 21 in number corresponding with the number of fuses mounted upon the sleeve. The ratchet-teeth are engaged in one direction by a spring-pressed pawl 22, pivotally attached to the operating lever-arm 23, which is pivotally connected to the end 4 of the arbor, and to the free end of the lever-arm is coupled a rod 24, leading to a point from which the lever-arm may be actuated. When the blades of opposite fuse-terminals are in position between the contact-plates of the binding-posts of the lead, the ratchet-pawl is in engagement with one of the teeth of the ratchet-wheel, and by moving the lever, as indicated by the arrow, the sleeve may be intermittently rotated to a degree to switch a pair of fuse-terminal blades out of contact with the plates of the binding-posts 17 and bring in contact therewith the next succeeding pair of terminal blades.

The degree of rotation of the reel by one movement of the lever is limited in one direction by a stop 25, so mounted upon the rod 24 as to contact at the end of the predetermined length of movement with a guiding-shoulder 26, and the ratchet-pawl 22 is always held in operative engagement with one of the ratchet-teeth of the wheel by a stop 27, preferably integral with the bearing 2 and adapted to limit the movement of the lever-arm in the opposite direction.

The rotation of the reel reversely to that which is imparted by the lever-arm is pre-

vented by a spring-pressed locking-dog 28, pivoted to the bearing and adapted to lock the ratchet-wheel against such movement.

To readily remove the arbor from the bearings 2 for removing one reel and placing another thereon, the bearings 2 are made sectional. In Fig. 3 the top section 29 of the bearing is hinged at one side to the bottom section 30, and the free side of the top is suitably bolted to the bottom section. However, if desired, both sides of the top half of the bearing may be bolted to the bottom section.

To use our fuse-magazine as a switch or circuit-breaker, we have provided gearing (illustrated in Fig. 4) in which a miter-gear 31 is mounted upon the end 4 of the arbor 2 and intermeshing with a gear 32, mounted upon the shaft 33, to the opposite end of which an operating-lever 34 is provided with a spring-pressed dog 35, adapted to engage with teeth 36, which are arranged in the arc of the movement of the lever and may be integral with a plate 37 and by spacing the teeth upon the plate provide an index by means of which any pair of fuse-terminal blades may be rotated to come into or break contact with the plates of the binding-posts of the lead.

By proportioning the gear 32 to the arc of movement of the operating-lever the sleeve may be made to describe a complete revolution within the extreme points of the movement of the lever, and by providing an initial blank section on the reel the circuit may be broken by rotating the reel to transfer the blank opposite to the binding-posts until one or more succeeding fuses are destroyed, after which the terminals of the last-burned-out fuse may be used instead of the blank for such purpose. The ratchet-wheel 20 may be also electrically actuated by providing a solenoid 38, Fig. 5, and form upon the free end of the core 39 a spring-pawl 40, which is adapted to engage one of the teeth of the ratchet-wheel. By energizing the solenoid through a shunt-circuit from the lead a core is drawn into the body of the solenoid a suitable distance to rotate the fuse-spiders to a degree to remove from contact with the plates of the binding-posts a pair of fuse-terminal blades and bring into contact therewith the blades of another fuse.

Upon the core there is secured a suitable stop 41, arranged to limit the outward movement of the same and engage the pawl with one of the teeth of the ratchet-wheel by contacting with a suitable shoulder 41'. A spring 42, surrounding the core, may be interposed between the stop and the solenoid to insure the outward movement of the core, and a reverse movement of the wheel is prevented by the locking-dog 28.

In the modification shown in Fig. 7 we have mounted a plurality of fuse-terminals 11^a upon a board 43, and each terminal of an opposite

pair is insulated from succeeding pairs by a division-wall 44. The fuse-board thus prepared is movable in ways 45 upon a back 46, to which the binding-posts for the ends of the 5 severed lead are secured in such position that the plates of a binding-post may contact with the blades of fuse-terminals on opposite sides of the movable board. The board may be moved by any suitable means to remove from 10 or bring into contact successive fuse connections with the binding-post plates of a lead.

Our invention is one that may be advantageously used wherever safety-fuses are required for the protection of vulnerable connections of a lead; but it is especially adapted for use in connection with the leads of car-motors. In street-car systems, where the maintenance of time schedules is of great economical as well as public importance and 20 where the burning out of a fuse frequently causes serious delays, which greatly interfere with such time schedule on account of the time required to replace it, such delays will be wholly avoided by the use of our magazine-fuse, whereby the circuit can be restored almost as quickly as it is broken by the burning out of a fuse, and by having the magazines made detachable and interchangeable when a magazine is exhausted it can be readily re- 25 moved and replaced by another fully supplied with fuses, or as the magazines are provided with a greater number of fuses than are ordinarily required for a day's service of the car an exhausted magazine can be refilled during 30 the time the car is out of service, and thereby avoid any delay during service hours by having to refill an exhausted magazine or to substitute a loaded one therefor.

What we claim to be new is—

40 1. In a magazine-fuse the combination of an insulating-base, a pair of lead-terminals mounted oppositely on the base each having a pair of contact-plates projecting parallel therefrom, an insulating-body movably mounted on 45 the base and adapted to move in either of opposite directions, a plurality of pairs of fuse-terminals the terminals of each pair being mounted oppositely on the body, a switch-blade integral with each fuse-terminal and projecting therefrom in position to be moved by 50 the body simultaneously with the blade of the opposite fuse-terminal between, and into and out of contact with a pair of lead-terminal plates, a T-shaped winding-post secured to 55 each fuse-terminal, a fuse-wire connecting

each pair of fuse-terminals by having its end portions wound taut around the end portions of the cross-bars of the winding-posts and then twisted back around the body of the wire, and means to move the fuse-bearing body to 60 successively connect each fuse in circuit with the lead-terminals by forcing the blades of its terminals between and into contact with the contact-plates of the lead-terminals.

2. In a magazine-fuse, the combination of 65 an insulating-base, a pair of brackets mounted on the base each provided with journal-bearings, an arbor journaled in the bearings, a pair of insulating-disks concentrically mounted on the arbor between the brackets, fuse- 70 terminal clips secured to the disks at regular intervals around the peripheries of the disks, the clips of one disk being placed oppositely and at equal intervals to the clips of the other disk, switch-blades integral with each clip ex- 75 tending radial to the disks with the sides of the blades parallel with the sides of the disks, a T-shaped winding-post secured radially to each clip with the cross-bar parallel with the switch-blade, fuse-wires connecting opposite 80 winding-posts by having their end portions wound taut around the end portions of the cross-bar on each side of the winding-post and then twisted around the body of the wire, a pair of lead-terminals mounted on the base 85 one in the plane of each disk, a pair of spring contact-plates secured to each lead-terminal and projecting therefrom in parallel planes on opposite sides of and touching the planes of the disk-blades, and means to rotate the ar- 90 bor and successively force the switch-blades of each fuse between the contact-plates of the lead-terminals.

3. The combination with a pair of fuse-terminals each having a T-shaped winding-post, 95 of a fuse-wire having its end portions wound taut around the end portions of the cross-bar of the winding-post on each side of the post and twisted back on the body of the wire for a distance from each post with the central 100 portion of the wire between the posts left uncovered by the twist.

In witness whereof we have hereunto set our hands this 7th day of November, A. D. 1902.
